UNITED STATES PATENT OFFICE.

SIEGFRIED HANSING, OF BOSTON, MASSACHUSETTS.

STRINGING PIANOS.

SPECIFICATION forming part of Letters Patent No. 341,603, dated May 4, 1886.

Application filed May 16, 1885. Serial No. 165,714. (No model.)

To all whom it may concern:

Be it known that I, SIEGFRIED HANSING, of the city of Boston, and State of Massachusetts, have invented a new and Improved 5 Piano-Forte, of which the following specification is a full, clear, and exact description.

This invention has reference to an improvement in dividing the different portions of the string between the pressure-bar (near the 10 tuning-pin) and the hitch-pin in such a manner that the "nodes" and ventral segments of the vibrations formed upon the string by the blow of the hammer may be in a certain proportion to each other, so as to establish a 15 greater purity and fullness of tone.

By intonating a string I desire it to be understood that the outer arrangements in connection with the main portion of the string will operate upon the latter in such a manner 20 as to produce a fixed number of "nodes and ventral segments" upon the string by which an exactly calculated aliquot division is obtained.

In order to make my invention perfectly comprehensible, and enable those skilled in the 25 art to make use of the same, I will first give an explanation of the principal features concerning the vibration of strings and how these vibrations are produced.

When a well-stretched string is made to vibrate, it forms one or more ventral segments, each of which terminates in two nodes, called 30 the "resting-nodes." The intermediate point of a segment I will call the "generating-node," at which place the operating power 35 is produced. For instance, if at this point the string is brought out of its position of rest by picking it with the finger or striking it with a hammer, then the string will be 40 divided in two equal half-segments, forming one complete segment and having a resting-node at each end. Contrary to the operating-power, acts the spring-power of the string, which, from said fixed ends or nodes, gradually 45 causes the vibrations to become rested.

It is the formation of nodes and segments upon a string which I have had particularly in view for my method of intonation. According to how this formation shall take 50 place, it must be carefully determined at what point of the string the hammer shall strike the same, and it is well known to piano-makers that the power and quality of tone

(timbre) greatly depends upon this circumstance.

Although Helmholtz, in his theory on musical acoustics, indicated one-seventh or one-ninth the length of the string at which point the hammer-stroke would give the best result of tone-quality, because of the removal thereby of the unharmonious seventh and ninth upper partials, which otherwise very unpleasantly combine with the balance of tone-substance contained in a vibrating string, yet no piano-maker has ever been able to positively 65 fix the point of hammer-stroke according to this idea, and at the same time obtain the much promised and indeed desirable results, which, according to my own theory and method of intonation, I trust may be accomplished.

The failure of a proper intonation heretofore may be explained in the following: The unequal division in itself is objectionable, for the reason that with one-ninth distance, for 75 instance, the hammer-stroke will form a ventral segment of two-ninths of the length of the string, transferring at the same time as many equal segments upon the whole length as two-ninths are contained in the same, giving a 80 result of four and one-half segments. Now, as one-half segment cannot possibly vibrate equally with the remaining four whole segments it must immediately destroy the division first formed and cause unevenness and 85 impurity of tone. The art of intonating a string properly therefore must have been a secret thus far.

In my opinion and experience it is the tenth part of the string where the hammer-stroke 90 will give an especially beautiful timbre, caused not only by giving the string a number of equal ventral segments, but also by my method of arranging those parts of the string which extend beyond its main portion over the sound 95 and resonance bridges, thereby giving greater prominence to the upper partials of "the third and fifth."

I will now illustrate what I have explained and what I shall add hereafter, by referring 100 to the accompanying drawings, in which—

Figure I represents a top view showing the arrangement of the strings for the middle and lower tones, and Fig. II represents a front view of the same.

a b represent the whole length of one of the

strings x , which is fastened at a to the hitch-pin g , and at the other end, b , to the tuning-pin B , the latter being inserted in the wrest-plank A .

5 s represents the pressure-bar, H the sound-bridge, S the hammer, and E the sound-board.

f represents the point where the hammer S strikes the string x , being the tenth part of the main portion of the same.

10 D represents the resonance-bridge, with its bridge-pins i and h .

F is the iron plate, with its hitch-pins g , the elevated ridge G , and the point l , bearing the strings.

15 e d , Fig. 2, represent two nodes having a ventral segment between them.

Having now determined the point f of hammer-stroke at one-tenth the length of the string, measuring from the point d on the sound-bridge H , I will now proceed to show my method of intonating the string to suit the above-mentioned hammer-stroke. The fact can easily be demonstrated that when the hammer strikes at the point f , this being the generating-node, and one half of the ventral segment being cut off by the sound-bridge H , the other half segment must (because f d is equal to f e) find its termination in the point e . This and the point d will form the two nodes of the first segment, and will measure two-tenths of the string's length. Through the stroke of the hammer—having formed said measured segment—a series of equal-sized segments in the form of wave-lines, as shown in

30 Fig. 2 in dotted lines, are now transmitted along the whole length of the string, and as one segment is measuring two-tenths there must be five complete segments contained in the string from the sound-bridge H to the bridge-pin h . This division brings into prominence the upper partial of the third.

35 A string is capable of a particularly audible sounding when made to vibrate while touching any of its aliquot divisions, while at any uneven division it will remain silent. Upon this fact must be based the phenomena of the upper partials, also called "harmonics." The following experiment will furnish the proof. Taking a little wooden wedge, and by pressing 40 it somewhat firmly upon the "third part" of the string nearest the sound-bridge H , which part can easily be found without much measurement, by letting the wedge slowly glide back or forward, while at the same time the string is 45 constantly agitated by means of the hammer-stroke, when the string begins to sound clear we will then have the "fifth" of the fundamental tone. It will now be seen at a glance that instead of the wedge, we can substitute the 50 sound-bridge or an agraffe for dividing the string and letting the usual pressure-bar take the place of the sound-bridge. The string will then respond to the outside agitation just as well as in the experiment with the wedge. 55 Although in practical piano-making it could not occur that a string with an inaccurate division would be completely silent while being

struck, because of the firmer support it receives at the sound-bridge than could be well given by the wooden wedge, still it will be sufficiently proved by my explanation that such string will not respond with such spontaneity as it does with correct apportionment of the "nodal points." Notwithstanding that, the pitch of the tone has its origin and emanates from the main portion of the string, extending from the sound-bridge H to the first bridge-pin, h , of the resonance-bridge D , we must take into consideration that the body of sound extends beyond the sound-bridge H to the pressure-bar c . With the same readiness that a string responds in the "one-third division," it will also do so in the division of "one-sixth," and, as by means of the hammer-stroke the string from the pin h to the sound-bridge H is divided into five ventral segments, it will be seen that the one-sixth division can be obtained by adding one segment from the sound-bridge to the pressure-bar, giving it the full lengths of the other ventral segments.

We will resume the experiment of the little wooden wedge. Having divided the string at one-third its length, we can, without silencing the string, subdivide its remaining two-thirds again in one-third each. The reason herefor is that when the vibrating string is divided at one third its length it forms immediately three equal ventral segments, the operating power of which exists in the center of the same, while the resting-nodes are "one" at each end of the string and "two" at one-third and two-thirds distance from those. Should we now interrupt the vibrating string by pressing it in the center of either one of the three segments, it would immediately become silent, for the reason heretofore explained—that the segment thus divided in two half-segments cannot possibly vibrate with the two remaining whole segments, and must 110 destroy, therefore, the operative power of the whole. This experiment proves, in the first place, that having determined the length of the string from the pressure-bar c to the point d on the sound-bridge, the whole length of the string from c to h will be divided in six equal parts. When the hammer is now made to strike at the point f , the generating-node of the string, the first segment, e d , being equal to the segment d c , the string will 115 then vibrate in six equal ventral segments. Secondly, having once adopted the length of the string from c to d the hammer must positively strike at the point f , the generating-node of the first segment d e . Otherwise, 120 should it, for instance, strike the string at e , it would immediately destroy the aptitude of the described equal division, as e in such case would be a generating-node and would form two and one-half segments upon the string, 125 which one-half, together with the one-half segment d c , would form two divided half-segments, which cannot vibrate in harmony with two whole segments. I have therefore adopted

the rule that the hammer must operate at the point f , the distance from the sound-bridge H being one-tenth part of the main portion of the string, and the distance from the sound-bridge H (the point d) to the pressure-bar e must be "double as long" as from the hammer-stroke f to the point d on the sound-bridge. It will now appear of vast importance that through my method of intonation the 5 harmonious upper partials of the seventh and ninth will be not only removed, but that, instead, the harmonious upper partials of the third and fifth are brought into greater prominence. It is well known that the portion of the 10 string which extends from the bridge-pin i to the point l on the elevated ridge G of the iron plate F has a particular influence upon tone substance and power, because it stands in direct connection with the resonance like the 15 main portion of the string. However, we must not consider the same as an independent sound-body, but must intone it, so as to operate most advantageously in assisting the tone substance heretofore obtained.

20 25 Experience teaches that objects, such as window-panes, loose metal work, stove-doors, &c., will vibrate when a certain tone whose number of vibrations are equal to those contained in said objects is brought in contact with the same.

30 Any other tones of unlike vibrations, including even the octaves of the former, have no influence upon these objects. In a piano-forte this influence of transporting tone-power is of great importance, and becomes more prominent 35 when the dampers are raised from the strings. This circumstance causes that every string in the instrument which contains the same number of vibrations (either as fundamental or partial tones) as the tone which is 40 produced by the stroke of the hammer will be divided in aliquot parts corresponding to those of said single tone, and therefore, through the additional increase of sound, will put the resonance in a state of particular activity. Upon 45 this fact I have based my method of intonating that part of the string which extends from the resonance-bridge pin i to the point l of the iron plate. If the same shall have the desired influence, its tone must be contained in the main portion of the string as 50 a "natural tone," or, vice versa, the tone of the main string, may be contained as a natural tone in that of the one to be intonated, as I will hereinafter show. As I have al- 55 ready established the division of the string from the bridge-pins to the pressure-bar, bringing in pre-eminence the upper partials of the third and fifth, it will appear most desirable to intone the indicated string beyond 60 the resonance-bridge for the same said upper partials, which, by doing so, will greatly add to the balance of tone-substance already obtained. If the length of the string from the left-hand bridge-pin to the ridge is one-fifth of 65 the length of the string from the right-hand bridge-pin to the sound-bridge, this fraction

will produce the third two octaves higher than the fundamental tone of the main string. Therefore this intonation applies particularly to the longer strings. In the drawings these 70 longer strings are designated as x' , and the bridge-pins, to which these strings are secured, as i' and l' . With these strings x' the distance of the string from i' to the ridge l is one-fifth the distance of the string from the 75 bridge-pins h' to the sound-bridge H . If the length of the string $i'l$ is one-third of the length $h'd$, then it will produce the fifth one octave higher, and therefore this intonation applies particularly to central strings—that is to say, 80 for the central strings, x , the distance $i'l$ is one-third of the distance $h'd$. As, however, the upper two octaves of a piano-forte (not shown in the drawings) do not to any extent acceptable to our ear contain this latter part 85 of the fifth one octave higher, it becomes necessary to intone the length of the strings from ridge to left-hand bridge-pin in said two octaves for lower combining tones, as three is in proportion to two. For instance, if the 90 main string is two inches long, the string from the ridge to left-hand bridge-pin must be three inches; or if the first is three inches the latter must be four and one-half inches, &c. Thus the relationship of these tones brought in 95 connection by striking the main string with the hammer will cause the above-mentioned activity of the resonance upon all its parts, obtaining thereby not only great tone purity, 100 but also more power of tone.

In order not to waste any part of the string that can accurately be employed for intonation, I have given the remaining string, which is situated between the point l and the hitch-pin g , a similar disposition as that obtained 105 in the string between the sound-bridge H and the pressure-bar e , differing from the latter in this manner. When the length of the string between $i'l$ is one-fifth of the main portion $h'd$, then the string $l'g$ must be either 110 one-tenth or one-twentieth of the length of the main string, and when the length $i'l$ is one-third of the main string, then the string $l'g$ must be either one-sixth or one-twelfth of the length of the main string.

Being aware that it is not new to have the point of percussion occur from one-ninth to one-eleventh of the string, I do not broadly claim such as of my invention.

I claim as my invention—
120 The combination, in a piano-forte, of strings x , hammer S , sound-bridge H , and bridge-pins h , the distance between the point of hammer-stroke and sound-bridge being equal to one-half the distance between sound-bridge 125 H and pressure-bar e , substantially as specified.

SIEGFRIED HANSING.
